GUIDE DEVICE

Stevenson Findlater, McKeesport, Pa., assignor
to National Tube Company, a corporation of
New Jersey

Application December 29, 1934, Serial No. 759,805

4 Claims. (Cl. 80—51)

This invention relates to a novel guide device which is particularly adapted for guiding a work-piece into or out of a metal-working mill, although not limited thereto.

5 In rolling mill practice it is extremely important that the proper entry and egress of the work-piece into and out of the pass be assured; otherwise serious complications result. The work-piece often "whips" to such an extent as to have 10 its quality impaired. This is particularly true in mills wherein rotation is imparted to the work-piece.

The proper guidance of the work-piece into and out of metal-working mills must therefore be 15 carefully regulated, and necessitates numerous changes in the guide devices employed. These changes are not required because of wear alone, but more frequently due to the fact that the mill must be employed to process a work-piece of a 20 different size, or cross-section. Most metal-working mills are capable of processing a range of sizes in work-piece cross-section, but the guide devices of the prior art are not so flexible in function, and must be frequently changed. Such changes often require several hours' time which occasions 25 a high cost of production, and often an entire loss of profit, particularly if a small order is being processed.

It is one of the objects of the present invention 30 to provide a novel guide device, which functions throughout a range of variations in work-piece cross-section, and one which at the same time may be easily and cheaply installed on existing types of metal-working mills.

35 Another object is the provision of a novel guide device which may be adjusted to accommodate various sizes, or changes in work-piece cross-section in a minimum of time.

The foregoing and further objects will be apparent after referring to the drawings, in which:

Figure 1 is a plan of the device of the invention in use on a conventional type of seamless pipe or tube mill.

Figure 2 is an enlarged plan of the device.

45 Figure 3 is an enlarged sectional view on the line III—III of Figure 2.

Figure 4 is an enlarged sectional view on the line IV—IV of Figure 3.

Referring more particularly to the drawings, 50 the letters A designate a pair of suitably actuated metal working rolls such as are commonly used in the manufacture of seamless pipes and tubes. A mandrel is frequently disposed between the metal-working rolls A for internally supporting 55 the work-piece being processed. In the present

instance, this mandrel is shown as a piercing plug B which is carried on the end of a suitably supported bar C, and is used to pierce a solid work-piece, as at W, to form a tubular shell. It is well known to those skilled in the art that considerable "whipping" of the work-piece takes place during this processing operation, and particularly after it has assumed a tubular form and is emerging from the mill.

The numeral 2 designates either an inlet and/or 10 outlet trough for a metal-working mill which is adapted to process a work-piece of substantially cylindrical cross-section. However, it will be readily apparent to those skilled in the art that the device of the invention is intended to be used 15 on any metal-working mill, regardless of the cross-section for which it is made, or adjusted.

A bed 3 is disposed on the floor of the mill immediately adjacent and in alinement with the trough 2 and carries a plurality of pairs of alined 20 bearings 4.

A rotatable shaft 5 is journaled in each pair of alined bearings 4 with its axis below, and at substantial right-angles to, the line of pass of the metal-working mill (not shown) and to 25 the axis of the trough 2. A cylinder 6 is secured to each of the shafts 5, and are each provided with a plurality of peripheral recesses 7, 8, 9, 10, 12, 13 and 14, which are of different cross-section, and arranged to extend at right angles to its 30 axis. That is to say, in the present instance the recesses 7, 8, 9, 10, 12, 13 and 14 are shown as being substantially U-shaped and of varying depth and width.

One end of each of the shafts 5 is provided with 35 an individual housing 15, in each of which there is disposed a worm gear 16 that is secured to the former. A common shaft 17 is extended through and journaled in all of the housings 15 and carries a series of worms 18, one of which 40 is adapted to mesh with each of the worm gears 16. The shaft 17 may be rotated in any suitable manner to aline the various recesses 7, 8, 9, 10, 12, 13 and 14 of the rotatable cylinders 6 immediately below the horizontal center line of the 45 trough 2. This permits the efficient guidance of a work-piece emerging from the metal-working mill (not shown) on the other side of the trough 2, the recesses 7, 8, 9, 10, 12, 13 and 14 serving to accommodate a rather wide range in 50 variations in its cross-section.

A shaft 19 is extended along the bed 3 immediately above the housings 15 on the ends of the shafts 5. This shaft is journaled in suitable bearings 20 and carries a plurality of laterally 55

extending arms 21. A semi-cylindrical sleeve 22 is carried on the extended end of each of the laterally extending arms 21 in such manner as to be disposed immediately above one of the cylinders 6. The concavity of each of the semi-cylindrical sleeves 22, conforms substantially to the shape of the recesses 7, 8, 9, 10, 12, 13 and 14 of the rolls 6, as indicated at 23 in Figure 3, so as to assist in the guidance of the work-piece. 10 A shaft 24 is extended along the bed 3 on its side opposite the shaft 19, and journaled in suitable bearings 25. This shaft 24 carries a plurality of laterally extending kick-off arms 26, which are alternately disposed with respect to the cylinders 6.

By suitable rotation of the shaft 17 the cylinders 6 are moved to align their respective recesses 7, 8, 9, 10, 12, 13 and 14. The shaft 19 is partially rotated to bring the laterally extending arms 21 into operative position, thus enabling the semi-cylindrical sleeves 22 to augment the function of the cylinders 6. After the laterally extending arms 21 are raised the shaft 24 is partially rotated to raise the laterally extending kick-off arms 26. The work-piece is thus raised by the kick-off arms 26 and permitted to roll transversely of the trough 2, preparatory to processing another work-piece.

30 Due to the ability of the mill operator to rapidly operate the various elements in the foregoing manner, changes to accommodate a different work-piece cross-section can be made practically instantaneously.

35 The cylinders 6 are provided at suitable points with indicia X in order to assure the positioning of the proper recesses.

While I have shown and described one specific embodiment of my invention, it will be understood that I do not wish to be limited exactly thereto, since various modifications may be made without departing from the scope of my invention, as defined by the following claims.

I claim:

1. A guide for metal rolling mills comprising at least one rotatable element having a plurality of recesses of varying cross-section in its periphery, and a separately movable cover for cooperating with said rotatable element, said movable cover being shaped to conform substantially to the cross-section of a work-piece to be rolled.

2. A guide for metal rolling mills comprising at least one rotatable element having its axis at 10 substantial right-angles with respect to the line of pass of said mill, said rotatable element having a plurality of recesses of varying cross-section in its periphery and in substantial parallelism with said line of pass, and a separately 15 movable cover for cooperating with said rotatable element, said movable cover being shaped to conform substantially to the cross-section of a work-piece to be rolled.

3. A guide for metal rolling mills comprising 20 a plurality of spaced rotatable elements, each having its axis at substantial right-angles with respect to the line of pass of said mill, each of said rotatable elements having a plurality of recesses of 25 varying cross-section in its periphery, said plurality of rotatable elements being connected for rotation in unison.

4. A guide for metal working mills comprising 30 a plurality of rotatable elements, each having its axis at substantial right-angles with respect to the line of pass of said mill, each of said rotatable elements having a plurality of recesses of 35 varying cross-section in its periphery, means for enabling the rotation of said elements in unison, and a movable cover for the periphery of each of said elements, each of said movable covers being constructed and arranged to cooperate with said recesses in such manner as to conform substantially to the cross-section of a work-piece being 40 processed by said metal working mill.

STEVENSON FINDLATER.
